UNITED STATES PATENT OFFICE.

GEORGE D. STULKEN, OF MCCOOK, NEBRASKA.

HAME-TUG CLIP.

SPECIFICATION forming part of Letters Patent No. 449,714, dated April 7, 1891.

Application filed August 1, 1890. Serial No. 360,711. (No model.)

To all whom it may concern:

Be it known that I, GEORGE D. STULKEN, a citizen of the United States, residing at McCook, in the county of Red Willow and State of Nebraska, have invented certain new and useful Improvements in Hame-Tugs; and I do hereby declare the following to be a full, clear, and exact description of the invention, such as will enable others skilled in the art to which it appertains to make and use the same.

The invention relates to the clip which connects the tug with the staple on a hame, and the replaceable wearing-piece of leather or other material which is often used to take the wear.

The invention consists in the particular means by which the wearing-piece is retained in its position, as hereinafter fully described.

Figure 1 of the drawings is a side elevation, partly in section, showing a clip connected with the staple of a hame, and provided with my invention. Fig. 2 is a detail perspective view of a wearing-piece to which is riveted a steel spring; and Fig. 3, a horizontal section of same.

In the drawings, A represents a clip, between whose arms *a a* is secured a tug B, by means of the rivets *b b*, while in the concavity of the curved bearing *a'* is secured a wearing-piece C, which is preferably made of leather or other suitable material. The use of this wearing-piece is very old; but the

question is how to conveniently and securely hold it in place, as it is constantly liable to work out if not provided with some fastening. For this purpose I employ the steel spring D, which is curved to hold the leather wearing-piece to which it is riveted near each end, and provided with the outward flanges *d d*, which embrace the bearing *a'*, and thus prevent the wearing-piece C from working out at either side of the clip. The piece C, combined with the embracing-spring D, may be readily put in the clip by pressing the sides together and then allowing them to spring outward against the inside of bearing *a'*. This holds the clip and wearing-piece together by friction, while the spring-flanges *d d* prevent the escape of the piece C from either side of the clip.

What I claim as new is—

The combination, with the end of a hame-tug clip and the wearing-leather therein, of an intermediate spring whose ends press outwardly against the inside of clip, are fastened to the wearing-leather, and are provided with flanges embracing the clip, as and for the purpose described.

In testimony whereof I affix my signature in presence of two witnesses.

GEORGE D. STULKEN.
